Des. 231,620
Patented May 7, 1974

231,620

TELEPHONE HAND-SET SUPPORT

Lyle H. Van Dyke, P.O. Box 14841,
Portland, Oreg. 97214

Filed Jan. 10, 1972, Ser. No. 216,867

Term of patent 14 years

Int. Cl. D14—03

U.S. Cl. D26—14 A

FIG. 1

FIG. 2

FIG. 1 is a top perspective view of the telephone hand-set support, and

FIG. 2 is an underside perspective view.

The broken lines representing the telephone hand-set in FIG. 2 are shown for illustrative purposes only.

I claim:

The ornamental design for a telephone hand-set support, as shown and described.
